UNITED STATES PATENT OFFICE.

EPHRAIM VIERTELS, OF NEW YORK, N. Y.

PROTECTOR FOR SHOES.

Application filed July 30, 1921. Serial No. 488,590.

To all whom it may concern:

Be it known that I, EPHRAIM VIERTELS, a citizen of the United States, residing at New York, in the county of Bronx and State of New York, have invented certain new and useful Improvements in a Protector for Shoes, of which the following is a specification.

My invention relates to a new and improved protector for the toes of shoes. One of the objects of my invention is to provide such a protector which shall render it possible to quickly, efficiently and economically repair shoes made of fine, soft leather such as, for example, fine ladies' shoes.

Another object of my invention is to provide a toe protector which can be adjusted so as to fit a series of different sizes of soles.

Another object of my invention is to provide a protector which shall be of substantially the same thickness and have substantially the same non-resilient properties throughout.

Other objects of my invention will be set forth in the following description and drawings which illustrate a preferred embodiment thereof.

Fig. 1 is a perspective view, showing my new and improved protector applied to a shoe.

Fig. 2 is a top view.

Fig. 3 is a front view.

Fig. 4 is a section along the line 4—4 of Fig. 2.

Fig. 5 is a perspective view.

The protector 1 as illustrated in Figs. 1, 2 and 5 is formed of a sheet of metal, preferably cold rolled steel about .020 inches in thickness. A medium cold rolled steel of this thickness has very little or no resiliency as this is preferable for enabling the article to be stamped and formed by means of suitable dies, as will be later more fully described, because experience has shown that if it is attempted to use a resilient metal, the manufacture of the article is more difficult and expensive and a relatively inferior article is produced since a springy sheet of metal cannot be shaped by dies so as to produce the desired contour.

To manufacture the article, a flat imperforate sheet of metal is first cut out by dies so as to have the general contour shown in Fig. 2, the outline of the said sheet of metal being substantially parabolic. The sheet of

metal is somewhat compressed during the cutting or stamping out thereof. I have not illustrated the dies or mechanism for cutting out the sheet of metal because this operation and the other operations involved in making my new and improved protector are in themselves well known to the art.

The said sheet of metal now has its edges turned up so as to form an upstanding flange 2, but it is preferable in forming the said upstanding flange not to compress the metal any further so that the sheet of metal has substantially uniform properties throughout. The top of the upstanding flange 2 is now turned over so as to provide an annular ledge 3 which is substantially parallel to the bottom of the protector and in turning over the said ledge, it is preferable not to compress the metal or change its properties.

A substantially V-shaped slit 5 is now cut in the bottom of the protector and another is cut in the ledge 3 thereof, so that the slit in the bottom of the protector extends up to the front wall thereof, and the ledge also has a V-shaped slit up to the front of the upstanding flange 2. The V-shaped opening in the top ledge 3 is identical in contour with that portion of the V-shaped slit in the bottom of the protector which is directly underneath it.

At the same time a series of perforations 6 are cut out of the bottom of the protector, as illustrated more clearly in Figs. 2, 4 and 6.

When it is desired to repair a fine shoe, the cobbler inserts the protector as illustrated in Fig. 1 with the ledge 3 between the top of the sole and the bottom of the upper and he then secures the protector by driving nails through the openings 6 and the sole of the shoe.

Of course, the top of the bottom of the protector is adjacent the bottom of the sole.

Since the bottom of the protector as well as the ledge thereof both have V-shaped slits formed therein, the protector can be spread out or narrowed so that a single protector can be used for a variety of sizes. The protector can be made in various colors so as to harmonize with the shoe to which it is to be applied.

I have described a preferred embodiment of my invention but it is clear that numerous changes and omissions can be made without departing from its spirit, and I do not wish

to be limited to the details herein illustrated.

What I claim is:—

A toe protector made of bendable metal comprising a bottom portion having a substantially vertical flange portion, and a turned-over ledge portion, the bottom of said protector and the said flange both having

slots extending to said flange portion, whereby by the said protector can have its size changed by merely bending the said flange. 10

In testimony whereof I hereunto affix my signature.

EPHRAIM VIERTELS.
